(57) CLAIM

The ornamental design for a combination garment bag and tote, as shown and described.

DESCRIPTION

FIG. 1 is an isometric view of the front of the unfolded combination garment bag and tote.

FIG. 2 is an isometric view of the back of the unfolded combination garment bag and tote.

FIG. 3 is a plan view of the front of the unfolded combination garment bag and tote.

FIG. 4 is a plan view of the back of the unfolded combination garment bag and tote.

FIG. 5 is an elevation view of the right side of the unfolded combination garment bag and tote.

FIG. 6 is an elevation view of the left side of the unfolded combination garment bag and tote.

FIG. 7 is an elevation view of the lower end of the unfolded combination garment bag and tote.

FIG. 8 is an elevation view of the upper end of the unfolded combination garment bag and tote.

FIG. 9 is an isometric view of the front of the folded combination garment bag and tote.

FIG. 10 is an isometric view of the back of the folded combination garment bag and tote.

FIG. 11 is an elevation view of the front of the folded combination garment bag and tote.

FIG. 12 is an elevation view of the back of the folded combination garment bag and tote.

FIG. 13 is an elevation view of the left side of the folded combination garment bag and tote.

FIG. 14 is an elevation view of the right side of the folded combination garment bag and tote.

FIG. 15 is a plan view of the top of the folded combination garment bag and tote; and,

FIG. 16 is a plan view of the bottom of the folded combination garment bag and tote.

The broken lines in the FIGS. 1-16 illustrate portions of the combination garment bag and tote and form no part of the claimed design.

1 Claim, 13 Drawing Sheets
